Original application October 16, 1930, Serial No.
489,145, Patent No. 1,976,585, October 9, 1934.
Divided and this application November 9, 1933,
Serial No. 697,268. In Austria October 19, 1929

8 Claims. (Cl. 200—46)

This application is a division of the copending application Serial No. 489,145, filed October 16, 1930, Patent 1,976,585 October 9, 1934.

This invention relates to a money delivering device in which the members, controlling the selective ejection of the different sorts of coins are controlled by perforated cards and consists in the provision of a common operating member and means for automatically rendering the latter operative by the presence of a card so as to cause the automatic operation of the card feelers and the coin ejecting control members of the coin disbursement device. In view of such provision the operation of the machine is considerably simplified and as its speed of operation is increased the efficiency of the machine is correspondingly increased.

In the present invention it is immaterial whether perforated cards are used for controlling the coin disbursement device as the perforated cards may be replaced by equivalent arrangements, such as perforated strips, cards or plates with registration indicating points, and the like. Further, the manner of representing values by perforations or registration indicating points of the cards or the like is quite immaterial to carry out the present invention. In the constructional example hereinafter described a perforated card is used in which each numerical value is represented by a corresponding number of successive holes arranged in a common row.

A device constructed according to the present invention is illustrated by way of example on the accompanying sheet of drawings in which:—

Fig. 1 is a diagrammatic sectional view of the machine showing the machine in a normal position and Fig. 2 is a similar view showing the machine in a partially operated position.

Fig. 3 is a detail view,

Fig. 4 shows a part of the perforated card and

Fig. 5 is a sectional view taken on the line 5—5 of Fig. 1.

Several rows of feelers 2, corresponding in number to the kinds of coins to be paid out, are arranged in a casing 1. Each row of feelers, related to a certain sort of coin, comprises nine pins. Springs 3, (Fig. 1) arranged on the feelers, force the latter through a slidably movable plate 4, which is provided with holes through which said feelers may project. By means of a pin 7 coacting with an angular slot 6 of a plate 5, it is possible to move the plate 4 for a purpose that will later be evident.

A second plate 8, provided with holes, is secured opposite the plate 4 and likewise, has holes through which the feelers may project. The top end of both plates are bent away from each other and thus provide outside of the casing 1 a funnel 21 for the insertion of the card. The feelers of a single row are angularly disposed in a vertical plane in such a manner that their right ends may limit the upward movement of a coin ejector 9. The latter consists of a lever which is provided with a longitudinal slot and is first slidable and then rotatable on a pin 10 engaging said slot and fixed to an operating lever 11. A spring 12 tends to retain the pin 10 in the bottom end of the longitudinal slot of the coin ejector lever 9. Further, the lower end of the coin ejector 9 has a pin and slot connection to a lever 13, which in conjunction with a lever 14, fixedly pivoted at one end, forms a toggle lever. A lever 15, pivoted to the joining pivots of the levers 13—14 is provided with a slotted end through which slot passes a pin 16 fixed to the operating lever 11. A spring 17 tends to turn the operating lever 11 in a clockwise direction about its pivot 18 so as to return it to its normal position shown in Fig. 1 after having been operated as shown in Fig. 2.

A slotted plate 20, (see Fig. 3) which forms a support for the coins inserted in the tube 21, is arranged opposite the hammer-shaped top end of the coin ejector 9 (Fig. 1). A sleeve or tube 22 slides on the tube 21 and rests on the top edge of the coin ejector. A funnel 23 is located opposite the coins of a related stack 35 and in connection with the corresponding funnels for the other sorts of coins they all terminate in a common collecting funnel 24, underneath of which is placed, for instance, a wage-receiving bag 25.

The device operates in the following manner:—

The perforated card 26 is inserted, reversed with respect to the position shown in Fig. 4, through the card insertion funnel 21 of the casing 1 until its top edge (which now faces downward) engages with the center partition 1a of the casing. In this position the holes of the card are disposed opposite the feelers 2. For instance, if according to the card shown in Fig. 4 the sum of \$26.23 is to be paid out, and if the group of feelers shown in the drawing serves for selecting the dollar units, the six holes in the card will be disposed opposite the six lower feelers 2. When the operating lever 50

11 is rocked counterclockwise by means to be subsequently described, the plate 5 moves downwardly to the Fig. 2 position and by the provision of the angular slot 6 the pin 7, and thus 5 the plate 4, are shifted to the left. The plate 4 releases the feelers 2 so that, by the action of the springs 3, the feelers move toward the card and at the places where they find holes in the card the feelers pass through the same. In 10 the present case the six bottom feelers pass through the card, while the three top feelers engage the face of the card as shown in Fig. 2.

During the further counterclockwise operation of the lever 11, the coin ejector 9 by means of 15 the spring 12 is elevated so far as is permitted by the six feelers which have been withdrawn from its path of movement. The coin ejector is positively stopped by the seventh feeler. During the last phase of the counterclockwise movement of the lever 11 beyond the Fig. 2 position the pin 16 cooperates with the top end of the slot in the lever 15 and forces upward the joining pivot of the two levers 13 and 14. Thereby, the coin ejector 9 rocks about the pin 10 and shifts 20 six of the oppositely lying dollar coins into the funnel 23. After this operation is performed the lever 11 is returned to its initial position by the spring 17. Now the joining pivot of the toggle lever 13, 14 is depressed by the pin 16 as shown 25 in Fig. 1 and the coin ejector returns to its normal position. At the same time the coin ejector is moved downwardly so that the coins in the tube 21 resting on the ejector 9 can slide down until they are stopped by the plate 20. 30 Owing to the weight of the sleeve or tube 22 it participates in the downward movement of the coin ejector, so that the unwanted coins are protected against accidental dropping into the funnel 23. During the last phase of the return 35 movement of lever 11 the plate 4 is shifted to the right by the reverse action of cam slot 6 on the pin 7 and thereby the feelers are forced out of the perforated card to the position shown 40 in Fig. 1 and the latter can now be freely removed by the operator.

A feature of the present invention consists 45 in causing the automatic operation of the operating member by the insertion of the card in the machine. This object may be attained for instance by providing a separate feeler, which is shifted from its position of rest whenever a card is properly disposed for registration with the feelers, and thereby renders operative automatically the feelers and the coin disbursement device.

When a card 26 is inserted in the machine to engage with the center partition 1a the said card cooperates with card actuated lever 28, which is in frictional contact (see Fig. 5) with a 50 contact lever 29. Card actuated lever 28 is moved from the position shown in Fig. 1 to the position shown in Fig. 2 and shifts the contact lever 29 from its position shown in Fig. 1 to its position shown in Fig. 2 to close contacts 55 30 when the card is in the position shown in Fig. 2. Thereby current passes through the magnet 31, which attracts the lever 11 and moves it in a counterclockwise direction. The latter, as previously described, causes the co-operation of the feelers with the card and the ejection of the desired coins. During the last 60 phase of the counterclockwise movement of lever 11 an extension 32 of the lever 11 strikes against the contact lever 29, shifts it independently of 70 the card actuated lever 28 which is held in rocked

position (Fig. 2) by the card to the position shown in Fig. 1 and against a pin 29a, and thus 5 opens the contacts 30. In view thereof, the magnet 31 becomes currentless and the lever 11 returns into the initial position by the action of the spring 17. When the card is manually removed from the machine by the operator 10 the lever 28 is returned to its initial position (shown in Fig. 1) by a spring 33 but lever 29 is prevented from moving by the pin 29a. The machine is now ready for the reception of the next card and the operation can be repeated.

Of course the number of the coin magazines and groups of feelers depends on the kinds of coins to be ejected by the machine. In the illustrative embodiment the vertical rows of feelers are arranged in such a manner that at their left they are separated from one another a distance equivalent to the vertical spacing of the rows of holes in the card, while their right ends 20 are vertically separated from one another a distance equivalent to the separation of the coin magazines.

What is claimed is as follows:—

1. In combination, devices adapted to coact 25 with an object, electromagnetically operated means for shifting said devices and object relatively, a member displaced by the object, contacts for controlling said electromagnetically operated means, a contact controlling member 30 having a connection with the first named member arranged to permit independent operation of said members but to cause a concurrent operation of both members to change a normal position of the contacts to effect an operation of the 35 electromagnetically operated means when the first-named member is displaced by the object, and means subsequently effective to cause an operation of the contact controlling member to restore the contacts to their normal position irrespective of the displacement of the first-named member by the object.

2. In a device of the character described, devices for engaging an object but normally separated from the object, a normally opened switch, 45 an electromagnet in series with said switch, means operated by the energization of the electromagnet to cause a shifting of said devices to engage the latter with the object, a member engaged by the object and displaced by 50 the object for closing said switch to cause the electromagnet to be energized, a supplemental member having a connection with the first-named member arranged to permit independent operation of said members but to cause a 55 concurrent operation of both members when the first-named member is displaced by the object, and means for causing the supplemental member to be operated to open said switch irrespective of the engagement of the member 60 with the object.

3. In a machine of the class described, in combination, an electro-motor for causing the operation of devices to coact with an object, a switch in the circuit of said electro-motor, a 65 member engaged and operated by the object, a second member having a frictional operating engagement with the first-named member and operated thereby for causing the operation of the switch, and automatic means for subsequently 70 operating the second-named member to open the circuit of said electro-motor and irrespective of the engagement of the first-named member with the object.

4. In a machine of the class described, in 75

combination, an electro-motor, a switch in the circuit of said electro-motor for controlling the operation thereof, resilient means, a two-part device having a connection arranged to permit an independent operation of both parts to cause a concurrent operation of both parts to close said switch against the action of said resilient means when one part is shifted from normal by an object, and automatic means for thereafter shifting the part not engaged by the object to open said switch, said resilient means thereafter shifting the part engaged by the object to a normal position when the object is removed from engagement therewith.

5 15. In a machine of the class described, in combination, an electro-motor, a switch for controlling the operation of said electro-motor, a member shifted from normal by an object, a second member having a frictional engagement 20 with the first-named member and shifted simultaneously therewith for closing said switch, automatic means for thereafter operating the second member to open said switch, and resilient means for causing the first-named member to 25 be shifted to normal when the object is removed from engagement therewith.

6. In combination, devices adapted to engage with an object, means for shifting said devices to engage with the object, means for 30 subsequently withdrawing said devices out of engagement with the object, a pair of members the first of which is engaged by the object to displace the second member to cause the opera-

tion of the shifting means, and means whereby the second member is shifted by the first named means to cause an operation of the withdrawing means whereby the devices are withdrawn out of engagement with the object.

5

7. In a machine of the class described, in combination, a switch, a solenoid having its circuit under control of said switch, an operating member operated by said solenoid, resilient means for restoring said member after its operation, a two-part device for closing said switch to cause the energization of said solenoid when one part is shifted by an object inserted in the machine, and means whereby said operating member prior to its restoration by said resilient 15 means causes the opening of said switch.

10

8. In a machine of the class described, in combination, a switch, a solenoid energized when said switch is closed to complete its circuit, an operating member operated by said solenoid, 20 means for restoring said operating member after its operation, a two-part device having a frictional connection therebetween and both parts concurrently operated to close said switch when one part is shifted by an object inserted in 25 the machine, and means whereby said operating member prior to its restoration causes the operation of the part not engaged by the object to cause said switch to be opened and by the opening of said switch the deenergization of the 30 solenoid.

GUSTAV TAUSCHEK.
